GOLF GAMEBOARD

Robert S. Liptak, Garfield Heights, Ohio, assignor to Hygrade Design Service, Inc., Cleveland, Ohio

Filed Mar. 19, 1973, Ser. No. 342,601

Term of patent 14 years

Int. Cl. D21—01

U.S. Cl. D34—5 GL

Fig. 2

FIG. 1 is a top plan view of a golf gameboard embodying my invention, shaded to show depth and gradations of tone; and

FIG. 2 is a perspective view of the board shown in FIG. 1.

I claim:

The ornamental design for a golf gameboard, as shown and described.
